(57) **CLAIM**

The ornamental design for a microscope, as shown and described.

DESCRIPTION

FIG. 1 is a front, top and left side perspective view of a microscope, showing my new design;

FIG. 2 is a rear, bottom and right side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and

FIG. 8 is a bottom plan view thereof; and,

FIG. 9 is an enlarged view of portion 9 shown in FIG. 2 thereof.

The evenly dashed broken lines illustrate portions of the microscope that form no part of the claimed design. The unevenly dashed broken lines in FIGS. 2 and 9 demarcate the enlarged views and form no part of the claimed design.
